UNITED STATES PATENT OFFICE.

FREDRICK WILLIAM HARRIS, OF WOODSTOCK, CANADA.

LOCK.

SPECIFICATION forming part of Letters Patent No. 518,884, dated April 24, 1894.

Application filed April 25, 1893. Serial No. 471,746. (No model.)

To all whom it may concern:

Be it known that I, FREDRICK WILLIAM HARRIS, of the town of Woodstock, in the county of Oxford, in the Province of Ontario, 5 Canada, have invented certain new and useful Improvements in Locks, of which the following is a specification.

My invention relates to improvements in locks more particularly adapted for drawers 10 and the object of the invention is to provide a simple, cheap and efficient lock, which will not readily get out of order or be liable to be picked and it consists in carrying down the bolt adjacent to the key guide and providing 15 a notch in the side of the bolt, which is designed to be engaged by the innermost bit of the key, a spring finger being also provided to operate against one of the bits so as to hold the bolt in position when shot or withdrawn, 20 and the whole being arranged in detail as hereinafter more particularly explained.

Figure 1, is a perspective sectional view showing my lock and the position of the parts when the bolt is withdrawn. Fig. 2, is a similar view showing the position of the parts 25 when the bolt is shot. Fig. 3, is an enlarged detail from the front showing the back plate, key guide, bolt and spring. Fig. 4, is a view from the inside of the drawer showing the 30 lock removed and the form of a groove or recess cut in the drawer.

In the drawings like letters of reference indicate corresponding parts in each figure.

A, is a portion of a drawer, which has 35 grooves, C', and, D', cut in it simultaneously by circular cutters commonly known and used for this purpose.

B, is a hole made through the drawer.

C, is the back plate of the lock which is fit- 40 ted into the groove, C', and, D, is the top plate which is attached to or forms part of the back plate, C. The plate, D, fits into the top of the groove, D', made in the drawer.

E, is a bolt which extends through a slot, e, 45 made in the top plate, D.

F, is the key-guide which is attached at the back to the plate, C, and has wards, f, through which the bits, g, of the key, G, pass as the key is turned.

e', is a V-shaped notch made in the side of 50 the narrow shank, E', of the bolt, E.

H, is a spring which is secured to the bolt, E, as shown.

h, is a projection forming part of the spring, which projects slightly into a notch, f' made 55 in the innermost ward of the key guide, F. When the locks are loose ready for shipping the bolt, E, will thus be prevented from shooting out of the lock.

I, is a bridge which it will be seen in the 60 drawings extends between the outer and middle ward. The sides of the bridge, I, are secured against the back of the plate, C, in any suitable manner.

i, is a lug forming part of the side of the 65 bridge I, bent inward and bearing against the shank, E', opposite the lower end of the spring, H. This projection i also limits the throw of the spring so that it will be impossible for any person to tamper with it and 70 throw it out of position. i', is a similar lug situated at the top of the side of the bridge, I, and designed to hold the bolt, E, against the plate, C.

f'', are projections extending from the two 75 sides of the key hole guide into the escutcheon, J, which is secured in any suitable manner to the drawer. The projections, f'', are tapped or riveted into the escutcheon plate, J.

Having now described the principal parts 80 involved in my invention I shall briefly describe its operation.

In Fig. 1, the key is shown with the bits ex- 85 tending downwardly the lower bit extending into the V-shaped notch, e'. By turning the key in the direction indicated the center bit, g, of the key comes against the spring and passes the same and the innermost bit, g, fits within the notch and by acting against it 90 raises the bolt into position shown in Fig. 2, 95 the top of the spring serving to control the upward movement of the bolt, E. To withdraw the bolt the key has to be turned in the opposite direction to that shown in Fig. 1, when the innermost bit, g, of the key will act against the ward and spring and withdraw the bolt into the position shown in Fig. 1.

From this description it will be seen that I

provide a very simple and efficient lock which it will be difficult to pick, and the parts of which it will be seen can be all stamped out and formed up very cheaply.

5 What I claim as my invention is—

1. In combination, a suitable casing, a bolt therein having a notched lower part E', a key guide having a series of wards, a spring H secured to the bolt and holding the same in 10 position and a key having bits, substantially as described.

2. The combination with the bolt, E, provided with the shank, E', and the key guide, F, provided with the wards, f, the innermost ward of which has a notch, f', of the spring, H, having the lug, h, designed to project slightly into the notch, f', as and for the purpose specified. 15

FREDRICK WILLIAM HARRIS.
